(57) **CLAIM**

The ornamental design for a vehicle interior, as shown and described.

DESCRIPTION

FIG. 1 is a perspective view of a vehicle interior showing my new design, showing one rear seat in a folded position and the other rear seat in an extended position;

FIG. 2 is a perspective view of the vehicle interior viewing the front thereof;

FIG. 3 is a close-up perspective view of the driver instrument area of the vehicle interior;

FIG. 4 is a front view of the vehicle interior viewed from in front of the driver position;

FIG. 5 is a close-up perspective view of the rear seat area of FIG. 1;

FIG. 6 is an elevational view of the rear seat area of FIGS. 1 and 6.;

FIG. 7 is an elevational view of the rear seat area of FIG. 6 with both seats shown in the extended position;

FIG. 8 is an elevational view of the rear seat area of FIG. 6 with both seats shown in the folded position;

FIG. 9 is a top plan view of the rear seat area of FIG. 6;

FIG. 10 is a rear perspective view of a seat of the vehicle interior;

FIG. 11 is a rear elevational view of the seat of FIG. 10;

FIG. 12 is a front elevational view of the seat of FIG. 10;

FIG. 13 is a side elevational view of the seat of FIG. 10;

FIG. 14 is an elevational view of the interior wall/door lining of the vehicle interior;

FIG. 15 is an elevational view of another interior wall/door lining of the vehicle interior;

FIG. 16 is a top perspective view of a door lining of the vehicle interior;

FIG. 17 is an end elevational view of the door lining of FIG. 16;

FIG. 18 is a top plan view of the door lining of FIG. 16; and, FIG. 19 is a top plan view of the vehicle interior.

In the drawings, the broken lines depict portions of a vehicle that form no part of the claim.

The claim is directed to the collective appearance of a vehicle interior. The separate pieces of the design have been shown for clarity, however the design is directed to the entire article as best seen in FIG. 19.
